United States Patent Office

Des. 212,675
Patented Nov. 12, 1968

212,675

CANDY BOX

Joseph Ehrenfeld, Clifton, N.J., assignor to
A. Klein & Co. Inc., New York, N.Y.

Filed Jan. 8, 1968, Ser. No. 10,072

Term of patent 14 years

(Cl. D9—174)

FIG. 2

FIG. 4

FIG. 1

FIG. 3

FIG. 1 is a top plan view of a candy box showing my new design;

FIG. 2 is an elevation as seen from the top edge of FIG. 1;

FIG. 3 is a side view thereof; and

FIG. 4 is a bottom view thereof on a reduced scale.

I claim:

The ornamental design for a candy box, substantially as shown.
